UNITED STATES PATENT OFFICE.

JACK A. SCANLAN, OF CHICAGO, ILLINOIS.

COMBINATION FURNITURE.

1,402,542.

Specification of Letters Patent. Patented Jan. 3, 1922.

Application filed March 26, 1920. Serial No. 368,894.

To all whom it may concern:

Be it known that I, JACK A. SCANLAN, a citizen of the United States, and resident of Chicago, in the county of Cook and State of Illinois, have invented certain new and useful Improvements in Combination Furniture, of which the following is a specification.

My invention relates to furniture and particularly to a combination adapted for use in 10 small apartments.

One of the objects of my invention is to provide a house furnishing element which shall be adapted for use in kitchens and to combine the functions of a kitchen table of 15 substantial size and a breakfast or luncheon table. It is not uncommon in small families and for certain meals to use the kitchen or kitchenette rather than the dining room, thus saving considerable work for the housewife. 20 However, kitchen tables as commonly constructed, are not available, either by reason of their arrangement or disposition for satisfactory use. Usually the table is placed against one or two walls, thus limiting the 25 seating capacity, and because of the provision of drawers or bins beneath the table top it is difficult to sit at the table in the usual manner.

In the construction here proposed I provide a kitchen table which possesses all the necessary features common to such tables and which by certain manipulation provides for four seats suitably arranged with relation to a second table disposed between the seats. 35 The result is accomplished in one form of the device by providing a pair of seats suitably spaced apart, the base beneath the seats being adapted to contain drawers or bins, the seats having backs which are hinged in such position that when swung into horizontal position they will lie in end to end relation and constitute a table top of substantial area. Disposed between the seats is an independently supported table, the top of which serves as a 40 support for the horizontally arranged backs of the seats and which, when the backs are in their normal or upright position, constitutes a table of ample proportions for the serving of a small meal.

50 In a modified construction the seats and seat backs are adapted to swing into horizontal end to end relation but the backs merely constitute a continuation of the top of an independently supported table located between the seats.

I also disclose a number of other novel fea-

tures which will be specifically described hereinafter.

The invention will be more readily understood by reference to the accompanying 60 drawing, wherein,

Fig. 1 is a front elevation of a combined furniture element as described;

Fig. 2 is a transverse vertical sectional view therethrough, the parts being shown in 65 their converted position.

Fig. 3 is an elevation of a modified form of construction, and,

Fig. 4 is a vertical sectional view therethrough showing the parts in a converted 70 position.

In the drawings it will be seen that I provide benches or seats 10, 11, which, in effect, form the top wall of boxes or bins 12, 13. These are indicated only in the elevation, it 75 being intended that they shall take such form as the constructor may desire. The seats are provided with side arms 14, 15, an arm being provided at each end of the seat or bench in the proper manner. The seat backs 16, 17, 80 are likewise provided with side arms or extensions 18, 19, and at the intersection of one point of the extensions 14, 15, with the extensions 18, 19, I provide pivots 20, 21, which act as hinges for the backs. By thus locating the 85 pivot at an elevated point with relation to the seat and by locating the pivot at a point considerably forward of the backs, I am enabled to so mount the backs that when swung into horizontal position they will assume the position shown in Fig. 1; that is, in end to end relation, thus forming a pair of flat surfaces adapted to function as a kitchen table top. The upper surface thus provided may be covered with any suitable material or left 90 unfinished. The lower surface, which constitutes the surface which is utilized as the back when the element is in raised position may be suitably finished.

The side arms of the seat and the back will 100 be artistically shaped, and as shown, the arms 18, 19, are cut away, as at 22, the edge of the cut away portion abutting the top surface 23, of the side arms 14, 15, which serves as a stop in the normal position of the backs.

In order to secure a finished appearance for the two positions of the device, I arrange the side wall 24, of the box, as best shown in Fig. 2, it being hinged, as at 25, to the back members 16, 17, and adapted for vertical movement. The lower portion of the side wall is notched as at 26, and the depending portion

overlies a fixed side wall 27, when the parts are in the position of Fig. 2. When however, the parts are in the position of Fig. 1, the two walls 24, 27, lie in edge to edge relation, 5 thus presenting a finished appearance and serving to lock the box in the relation shown in Fig. 1. When it is desired to swing the backs, the side walls 24 are moved outwardly sufficient to enable the lower edges thereof to 10 pass the fixed walls 27.

In order to provide a foot rest for children, I may prefer to so arrange the inner walls 28, of the backs that a portion 29, thereof may be swung outwardly on hinges 30, the outward 15 movement being limited by suitable means such as the chain 31.

The seat members heretofore described will be secured in fixed spaced relation, and located between the seat members is a table 20 consisting of a top 32, and supporting legs 33, which may be connected near their lower ends by a cross bar 34. This table will likewise be held in a fixed position and the height of the top is so proportioned that it serves as 25 a support for the back members constituting the main table top when in horizontal position.

In the construction shown in Figs. 3 and 4, the base members 35, which are adapted 30 to contain the drawers, provide the seats 36. the back wall of the base member being fixed and extending upwardly to a point somewhat above the seats 36. Hinged to the upper extremity of the back wall 35 in 35 each case is a section 37, of a table top, provided with side members 38, which constitute side arms when the parts are in the position shown in Fig. 4. The seats 36 are likewise provided with side arms 39, a portion 40 of which is of increased height. Hinged to the portion 40 is a lock 41, adapted to fill the space between the side arm and the side member 38 of the top when the latter is in raised position. When the parts are 45 in the position shown in Fig. 4, the member 37, which in that position constitutes a portion of the back of the seat, is locked in place and cannot be lowered into the position of Fig. 3 until the hinged member 41 50 is swung inward.

As in the preceding case, I provide an intermediate table 42, independently supported on legs 43, the table top, together with the members 37, when in horizontal 55 position constitute a table top of extended area but which may readily be converted into a useful adjunct to a small apartment.

It will be understood that while I have described constructions in which there are 60 two seats, one on each side of an independent table, this might be varied to the extent of eliminating one side if desired.

A piece of furniture constructed as described will combine many desirable features 65 which are absent in the kitchen table con-

structions heretofore proposed. All the advantages of an ordinary table are present and in addition the device may be spread apart and utilized as described, thus eliminating the necessity for a plurality of chairs 70 and an additional table in the kitchen. It is, of course, understood that its use is not limited to a kitchen nor is the form and arrangement of the component parts an essential element. I do not wish to be limited 75 therefore except as indicated in the appended claims.

I claim:

1. In combination furniture, a pair of seats arranged to face each other and provided with hinged backs, and a table disposed between the seats and acting as a support for the backs when in lowered position, the reverse side of the seat backs acting as a table top, substantially as described. 80

2. In combination furniture, a table top divided transversely to form two sections, end portions including a flat wall adapted to act as a seat, side arms, the top sections being pivoted to the side arms, and an intermediate independent table the top of which is adapted to act as a support for the top sections when in lowered position, substantially as described. 90

3. In a device of the class described, the combination of a pair of seats arranged in spaced relation, a table located between the seats, and seat backs hinged to the seats and adapted in folded position to mate and overlie said table, the reverse surfaces of 100 the seat backs forming a table top of materially greater area than that of the first mentioned table, substantially as described.

4. In a device of the class described, the combination of a pair of seats arranged in spaced relation, a table independently supported between the seats, and seat backs hinged to the seats and adapted to be folded horizontally in end to end relation over the seats and over said table to form a second 105 and larger table, substantially as described. 110

5. In a device of the class described, the combination of a pair of seats arranged in spaced relation, the seats having side arms, a table independently supported between the seats, and seat backs hinged to the side arms and adapted to be folded horizontally over the seats and over said table to form a superposed table, substantially as described. 115

6. In furniture, the combination of a pair of seats having supports adapted to contain drawers, a table independently supported between the seats, and seat backs hinged to the seats and adapted to be swung 125 into horizontal end to end relation over the seats and the table to form a superposed table top, substantially as described.

7. In furniture, the combination of a pair of benches spaced apart, a table inde- 130

pendently supported between the benches, said benches having side arms, backs for said benches, said backs having side extensions, and means for pivoting said extensions to the side arms whereby to permit the backs to be swung into horizontal end to end relation and thereby to overlie said table, substantially as described.

8. In furniture, the combination of a bench, a table independently supported in spaced relation from the bench, a back hinged to said bench and adapted to be swung into horizontal position to overlie and be supported on said table and form a table top of greater area than that of said table, substantially as described.

9. In furniture, the combination of a seat, supporting means for the seat, said means being adapted to contain drawers, side arms for the seat, a seat back hinged to said side

arms, and a table independently supported adjacent to said seat and so positioned that said seat back may be swung to a horizontal position to overlie the table, substantially as described.

10. In furniture, the combination of a seat having a side wall, a portion of said side wall being hinged and adapted to swing into a substantially horizontal position to form a foot-rest, a table independently supported adjacent to said seat, and a seat back hinged to the seat and adapted to be swung into horizontal position to overlie the table, substantially as described.

Signed at Chicago, Ill., this 22nd day of 35
March, 1920.

JACK A. SCANLAN.
